MOBILE HOUSING FOR CONDUCTING HEARING TESTS

Carl-Axel Tegner, Majorsgatan 17, Stockholm, Sweden

Filed July 29, 1971, Ser. No. 167,563

Claims priority, application Sweden Feb. 12, 1971

Term of patent 14 years

Int. Cl. D24—01

U.S. Cl. D83—1 F

Fig 1

Fig 2

Fig. 4

Fig. 3

FIG. 1 is a perspective view showing a mobile housing for conducting hearing tests, with the front door in closed position;

FIG. 2 is a perspective view showing the container of FIG. 1 having the entrance door in open position;

FIG. 3 is a perspective view of the side opposite to FIG. 1; and

FIG. 4 is a rear view of the mobile housing.

I claim:

The ornamental design for a mobile housing for conducting hearing tests, as shown and described.
